(57) **CLAIM**

The ornamental design for a louver for a skin humidifier, as shown and described.

DESCRIPTION

FIG. 1 is a front perspective view of a louver for a skin humidifier showing our new design;

FIG. 2 is a front view thereof;

FIG. 3 is an enlarged view of the portion indicated with the number 3 in FIG. 1;

FIG. 4 is an enlarged view of the portion indicated with the number 4 in FIG. 2; and,

FIG. 5 is a perspective view showing the louver for a skin humidifier independent from its environment.

The dash-dash broken lines illustrating a skin humidifier depict environment and form no part of the claimed design. The dot-dash broken lines depict the boundary lines of the enlarged detail views and form no part of the claimed design. The broken lines in FIG. 5 illustrate portions of the louver for a skin humidifier that form no part of the claimed design.
